DESIGN FOR A BOTTLE

Paul Peter Mülhens, Cologne, Germany

Application March 6, 1936, Serial No. 61,499
In Great Britain December 30, 1935

Term of patent 14 years

To all whom it may concern:

Be it known that I, Paul Peter Mülhens, a citizen of the German Reich and residing in Cologne, Germany, have invented a new, original, and ornamental Design for a Bottle, of which the following is a specification, reference being had to the accompanying drawing, forming part thereof.

I claim:

The ornamental design for a bottle, as shown.
In testimony whereof, I affix my signature.

PAUL PETER MÜLHENS.
